D11-161. OR D20,426 EX

DESIGN FOR A STATUE OF A FIREMAN.

Design No. 20,426, dated December 23, 1890.

UNITED STATES PATENT OFFICE.

CHARLES G. DEMUTH, OF NEW YORK, N. Y., ASSIGNOR TO J. W. FISKE, OF SAME PLACE.

DESIGN FOR A STATUE OF A FIREMAN.

SPECIFICATION forming part of Design No. 20,426, dated December 23, 1890.

Application filed November 24, 1890. Serial No. 372,561. Term of patent 7 years.

To all whom it may concern:

Be it known that I, CHARLES G. DEMUTH, a citizen of the United States, residing at 415 East Eighty-first street, New York, in the county of New York and State of New York, have invented a Design for a Statue of a Fireman, of which the following is a specification.

My invention consists of a design for a statue of a fireman, as shown in the accompanying photograph, to which reference is hereby made.

As shown in the accompanying photograph, the design represents the figure of a man dressed in the garb of a fireman and holding on one arm a child and carrying in his other hand a lantern.

The design is intended to represent the heroic action of the fireman in having rescued the child from a burning building.

Instead of a lantern, a hose-nozzle or any similar implement indicative of the guild or service may be substituted, or the lantern or other implement may be omitted entirely, without changing the design, which consists of the figure of a fireman holding a child, substantially as shown.

What I claim as my invention is—

The design for a statue of a fireman, as herein shown and described.

In witness whereof I hereunto set my hand in the presence of two witnesses.

CHARLES G. DEMUTH.

Witnesses:

JOHN W. FISKE,
WILLIAM H. SMITH.
